UNITED STATES PATENT OFFICE.

BYRON Q. JONES, OF WASHINGTON, DISTRICT OF COLUMBIA.

DIAPHRAGM MUFFLER.

Application filed July 12, 1924. Serial No. 725,622.

This invention relates to telephone receivers, the broad object in view being to produce a muffler for the diaphragm of a telephone receiver which can muffle the unpleasant "cracks" due to static and similar causes and which will also muffle the metallic ringing of the diaphragm without interfering with the audibility of the signals which it is desired to receive.

Another object of the invention is to produce a telephone receiver muffler of simple construction which may be quickly applied in position whenever desired. With the above and other objects in view, the invention consists in the novel construction, combination and arrangement herein more fully described in the attached specification, and in the claims.

In the accompanying drawings:

Fig. 1 is a side elevation of a portion of a telephone receiver showing the muffler installed in position, and

Fig. 2 is an end elevation of Fig. 1.

Referring to the figures more particularly by reference numerals, a telephone receiver 1 is provided with a diaphragm 2 against which is held a pad of suitable soft material

such as felt, by means of a wire or spring 4 which is bent so that the pad is held resiliently against the diaphragm. The spring 30 4 is so designed that it will easily grip over the telephone receiver in the manner indicated so as to hold itself in position. As shown, the spring extends from the center of the receiver radially outward and is then 35 bent substantially at right angles so as to extend along the back of the flange of the end of the receiver.

I claim:

1. A device for muffling the diaphragm of 40 a telephone receiver comprising a muffling pad and a spring clip formed to engage the exterior of the receiver and adapted to resiliently hold said pad against said diaphragm.

2. In a device for muffling the diaphragm of a telephone receiver, a spring wire bent to fit about the edge of said receiver, a muffling pad secured to the inner end of said wire and adapted to be resiliently held against 50 said diaphragm for the purpose described.

In testimony whereof I affix my signature.

BYRON Q. JONES.
